2,853,787

PIN GAUGE

Edwin M. Dyer, Greenville, Ky.

Application July 12, 1957, Serial No. 671,551

7 Claims. (Cl. 33—174)

This application relates to well drilling equipment and more particularly to pin construction, gauge for said pin construction, and the method of gauging such pin.

An object of this invention is to provide a pin forming part of a box and pin joint, particularly for use in cable tools used in drilling wells, such as oil wells, and the like.

Another object of this invention is to provide a pin which may be gauged to determine whether it has undergone distortion of such order that failure of the pin is imminent.

Another object of this invention is to provide a pin, the likelihood of failure of which is predictable, whereby pin failure and resultant loss of portions of the drilling string in the well hole may be avoided.

A further object of this invention is to provide a gauge of simple, durable construction for use in gauging pins of the foregoing character to determine if same have been elongated, bent, twisted, or otherwise distorted excessively.

A further object of this invention is to provide a gauge which may be used to gauge pins of the foregoing character in order that defective pins which are likely to fail in use, may be rejected prior to insertion in a string of tools.

A further object of this invention is to provide a gauge which is durable and will withstand use at the drill site to gauge pins of drill string elements prior to their connection in a drill string.

A further object of this invention is to provide a method of testing pins to determine their suitability for use.

The above and other objects and features of the invention will in part be obvious, and in part be apparent to those having ordinary skill in the art to which this invention pertains.

Like reference characters indicate like parts in the following description and accompanying drawing, in which:

Fig. 1 is a view in side elevation of a string of tools embodying the present invention, portions of some of the elements thereof being broken away to avoid excessive size of the particular view.

Fig. 2 is a view in perspective of the end portions of an element of a drill string the central portion of the element being broken away to reduce the size of the view but without effecting the portions of the structure relevant to the instant disclosure.

Fig. 3 is a view in perspective of the end portion of a drill string element showing a pin embodying the present invention.

Fig. 4 is a view in side elevation, partly broken away to illustrate the construction of a gauge embodying the instant invention and showing the gauge in co-operative relation to a pin embodying the instant invention.

Fig. 5 is a top plan view of a portion of the hub portion of the gauge illustrated in Fig. 4.

Fig. 6 is a plan view in side elevation of one of the L-shaped arms forming part of the gauge and adapted

2

to be secured in co-operative relation to the gauge hub shown in Fig. 5.

Fig. 7 is a fragmentary view in section, taken along the line 7—7 in Fig. 4.

5 Fig. 8 is a fragmentary view in side elevation taken along the line 8—8 in Fig. 4; and

Fig. 9 is a fragmentary view in side elevation of an unsatisfactory pin in co-operative relation to a fragmentary portion of a gauge corresponding generally to the view Fig. 8.

A string of cable tools such as may be used in the drilling of wells such as oil wells, or the like, is illustrated in Fig. 1. The several elements comprising the string of tools may be varied from time to time, but one such assembly of elements used when drilling a well comprises those illustrated in Fig. 1. To the lower end of a cable or rope 20 is secured a rope socket or swivel 21 which in turn suspends a unit known as jars 22 to the lower end of which is coupled a drill stem 23, the lower end of which is coupled a drill bit 24. It may be noted that the drill stem 23 is primarily a long, heavy steel bar and the center portion of the stem has been broken away in preparing the illustration thereof in Fig. 1. It is customary to form the end portions of the several elements which may be incorporated in a drill string such as the one illustrated in Fig. 1, according to standard dimensions in order that the several elements may be assembled in any desired sequence and combination.

15 Each element of the drill string has a box end and pin end. In Fig. 2, are shown the end portions of a drill string element, the center portions of which have been broken away, and as oriented in Fig. 2, the box end portion 26 is shown as the lower end portion and the pin end portion 27 is shown as the upper end portion.

20 35 As shown in Fig. 2, a frustoconic recess 28 extends axially upward into box end portion 26 and is surrounded by a flat, annular, radial surface. As shown most clearly in Fig. 2, threads 30 are provided in the wall of the frustoconic recess 28 to co-operatively receive a threaded pin incident to coupling the drill string element shown in Fig. 2 to another element not shown.

25 The pin end portion 27 of the drill string element shown in Fig. 2, has a flat, annular, radial face 31 parallel to face 30 on box end portion 26 and pin 32 extends axially from face 31 and is in axial alignment with box recess 28. The pin 32 is generally frustoconic in shape with its major base coplanar with the plane of face 31 and its minor base being the end face 33 which is the free end face of pin 32. The outer frustoconic face of pin 32 is threaded and the threads 34 thereon are adapted to mate with the threads 30 in the frustoconic wall of box recess 28. It is customary to provide on each of the drill string units or elements, a portion having parallel faces, the portion usually being of square, cross-section to provide surfaces adapted to co-operate with wrenches used in drawing the threaded joints into tight co-operation.

30 40 In Fig. 2 the faces adapted for engagement by a wrench are indicated by the reference character 35, and are often referred to in popular parlance as "squares." The proper tightening of box pin joints and the method of properly tightening them form part of the skills possessed by one or more of every drilling crew. If the joint is tightened too tightly, the pin 32 may be elongated and thereby weakened; and if insufficiently tightened, the joint may open while the string is in use in the well hole being drilled. If a joint opens, or if a pin fails, while the drill string is in the hole, the portion of the drill string below the point of failure, is lost and its recovery is an expensive, time-consuming operation which must be completed before it is possible to continue drilling the well deeper. Box and pin joints would be found in the drill string illustrated in Fig. 1 at the locations in

45 55 60 65 70 75 80 85 90 95

dicated by reference character 36, the lead line of which indicates the plane of abutment between co-operating angular shoulder faces 29 and 31.

The drill string must be pulled from the hole from time to time and disassembled incident to replacement of drill bits 24 as they become dulled, or for the addition or removal of other tools which may be used from time to time. Over an extended period of use it is usual that the pins 32 tend to stretch or elongate and become otherwise distorted, i. e., tend to bend and/or tend to twist or wring off adjacent the plane of the annular surface 31. As shown in Fig. 1, the frustoconic recess 28 in the box portion of the drill string element has a depth greater than the length of the pin 32 which is adapted to be threadedly received therein. This greater depth permits appropriate tightening.

When the pin 32 is distorted, it is weakened and must be returned to the shop where a portion is cut off of the end of the pin and the element is machined to the standard pin form and dimension before it is returned to a drill site for further use. The detection of defective pins is quite difficult. The cost of remachining the pin portion of a drill string element is not negligible, but it is much less than the cost of recovering lost portions of a drill string from a hole. In order to detect defective pins, I provide on the drill stem elements a pin of the kind shown in the drawings, particularly in Figs. 3 and 4, the general dimensions of which may be those of a standard pin in order that it may be used in conjunction with standard box end portions. The pin 32 shown in Fig. 3 has an axial recess 37 extending into its radial end face 34. The wall of the recess 37 adjacent radial end face 34 tapers frustoconically, and the taper may be in conformity with the taper of a lathe center used when the pin portion is machined. As is shown more clearly in Fig. 4, the wall of the lower portion of recess 37, that is, the portion spaced from radial end face 34 may be cylindrical in form and threaded. Radially oriented V-grooves 40 and 41 are provided in radial end face 34. V-groove 40, as shown, may be narrower than V-groove 41 and they are aligned along a common diameter. A pair of oppositely positioned longitudinal grooves extend radially into pin 32 from adjacent annular shoulder face 31 to a point intermediate the plane of face 31 and radial end face 34. As shown in Fig. 3, the grooves are designated by the reference characters 42, 43. Groove 42 is narrower than groove 43, just as V-groove 40 is narrower than V-groove 41. The center lines of the grooves 40, 41, 42 and 43 are coplanar with the axis of pin 32. Groove 42 has spaced side walls 44 which are parallel to the plane of the center lines of grooves 40, 41, 42 and 43, and a bottom 45 which is parallel to the bottom 46 of groove 43. The side walls of groove 43 are also in spaced parallel relationship to each other and the previously mentioned center line plane. The end walls corresponding to end wall 47 of groove 42 are preferably coplanar with annular shoulder face 31, or as nearly so as possible.

A gauge means which may be used to check the degree of distortion of a pin 32 prior to the assembly, of the drill string element of which it is a part, in a drill string at the drill site may be constructed in the following manner. A hub member 50 which may be of right cylindrical form, as shown, is provided, having an axial bore 51 extending therethrough, the bore 51 is frustoconic adjacent one of its ends and tapers from its one end to a right cylindrical portion adjacent its other end, the frustoconic portion of the bore 51 being bounded by a frustoconic wall 52 and the right cylindrical portion thereof being bounded by a cylindrical wall 53. A pair of diametrically opposed slots 54, 55 are provided in hub 50 and extend radially inwardly from the periphery thereof and terminate in spaced relation to bore 51. As shown in Fig. 5, slot 54 is narrower than slot 55 and spacing of the lateral wall faces of the slots which

extend parallel to an axial plane of hub 50, for example, spacing of wall faces 56 and 57 bounding slot 55, is preferably held to close tolerance for the reasons which follow.

In Fig. 6 is shown a plan view of an L or arm member 58 which has two flat, parallel, L-shaped faces 59. The thickness of the L-shaped member 58, that is, the spacing of the faces 59 thereof, is of such magnitude that the shorter arm portion of member 58 may be pressed into slot 55, wherein it is firmly engaged and anchored between the faces 56 and 57 bounding that slot. The relationship of the arm of the L-shaped member 58 to the hub 50 is shown most clearly in Fig. 4. The shorter arm portion of element 58, as shown clearly in Figs. 6 and 4, has a knife edge 60 which extends from the longer arm portion of that element to the free end of the shorter arm portion thereof. The knife edge 60 is the line of intersection of the plane bevel faces 61, 62. As shown in Figs. 4 and 7, the faces 61 and 62 do not extend into the slot 55, and thus project from the radial face of hub 50. A second L-shaped member 64 is similar to L-shaped member 58, and differs therefrom only in thickness, that is, the spacing of the L-shaped faces 65, 66 is not equal to the spacing of the L-shaped faces 59 of member 58. The L-shaped member 64 is placed in co-operation with hub 50, namely, with a portion thereof in slot 54 in a manner similar to the manner in which L-shaped member 58 is secured to the hub. As shown in Fig. 4, the long arm portions of the members 58, 64 extend in spaced, parallel relation to the axis of hub 50, while the shorter arm portions having knife edges 60, 67, extend in parallel relationship and radially of hub 50. Thumb screw 68 has a head 69, a frustoconic body portion 70 tapering from head 69 to a cylindrical portion 71 upon which external threads 72 are provided. The screw 68 is shaped and dimensioned to extend through bore 51 with its frustoconic body section 70 in mating relation with the frustoconic wall portion 52 of the bore 51 and its cylindrical portion 71 extending through the cylindrical portion of bore 51 into threaded engagement with pin 32, the threads 72 thereof being in engagement with the threads 39 in the cylindrical portion 38 of the axial recess in pin 32. The thumb screw 68 may be rotated to draw hub 50 axially toward radial end face 34 of pin 32. The projecting knife edges 60 and 67, respectively, extend into V-grooves 41 and 40. The under side 73 of thumb screw head 69 being a radial face and engaging the radial face of hub 50, whereby the gauge is drawn into proper alignment with the center lines of the long arms of the L-shaped portions extending in parallel relation to a diametral axial plane of pin 32 in which the apices of the V-grooves 40 and 41 also lie. The long arms of the L-shaped members 58 and 64 thus extend into and longitudinally of grooves 42 and 43, the free end faces 77, 78 of those arms being positioned in close spaced parallel relation to annular shoulder face 31, when screw 68 is turned down tightly to clamp the gauge in gauging relation to the pin 32.

When the gauge is mounted in co-operative relation to a pin 32 which is undistorted, the long arm portions of the L-shaped members 58 and 64 extend in the respective grooves 43 and 42 in a manner corresponding to that illustrated in Figs. 4 and 8. In Fig. 8, the long arm portion of L-shaped member 64 is designated by the reference character 75. As shown, the portion 75 extends into slot 42 with its face 65 in close spaced parallel relationship to side wall or face 44 of groove 42 and its face 66 in close spaced parallel relationship to groove side wall or face 76. The spacing between faces 65 and 64 and between faces 66 and 76 may be of any order desired. However, I have found that spacing may be conveniently of the order of 0.020 inch. The end face 77 is in close spaced parallel relationship to annular shoulder face 31, as is end face 78 on the other arm of long leg of the

L-shaped member 58. The faces 77 and 78 are coplanar, perpendicular to and parallel to the knife edges 60 and 67. It may be noted that the edge faces 79 and 80 of the respective long arm portions of members 64 and 58 are spaced from the bottom face of the grooves, as is shown in Fig. 4. Thus, when the gauge is mounted in the fashion described in co-operative relation with a pin 32, the long gauge arms being in spaced parallel relation to the several faces, namely, the side walls of the respective grooves and the annular radial shoulder face 31, the pin may be tested for distortion by passing a simple feeler gauge, such as is widely used, for example, in gauging the gap between the electrodes of a spark plug for an internal combustion engine, between the close spaced faces. Bending of the pin may be indicated by the existence of a non-parallel relationship between faces 65, 44, or 66, 76, or the corresponding faces of the other arm of the gauge, or by the spacing between face 78 and 31 being unequal to the space between faces 77 and 31. Since the gauge is initially applied to the pin before it is placed in use, namely, when the element of which it is a part, is received from the factory or machine shop, the spacing dimensions referred to in the foregoing description may be noted at that time for future reference in determining variations in any of those dimensions. Thus, the spacing of faces 78 and 77 from face 31 is known at the outset, elongation or stretching of the pin will be indicated by an increase in the spacing between faces 78, 77, and 31. The other change of the pin which is a prelude to its failure is a twisting thereof and the twisting normally is found to occur in the portion of the pin adjacent face 31. Assuming that Fig. 8 is an illustration of a pin which has not been distorted, we may view Fig. 9 as the same pin as subsequently distorted, particularly it may be noted that the spacing between faces 77 and 31 is greater in Fig. 9 than in Fig. 8. This may indicate bending along the axis of the pin. It may indicate stretching of the pin. Further, it may be noted that the walls 44 and 76 are not parallel to the faces 65 and 66 of the gauge portion 75. In this case it may be noted that the face 66 is in substantial contact with face 76 at the points indicated by the reference characters 82 and 83, while face 65 is nearly in contact with face 44 at point 84. Thus, if the tester sought to slide a twenty-thousandths inch feeler gauge blade between these faces, that feeler gauge blade would bind between the faces 65 and 44 as it approached the vicinity of point 84 and would be loose in the vicinity of the point indicated by the lead line from the reference character 44 in Fig. 9. Of course, if the pin 32 had been twisted more than is shown in Fig. 9, it might be impossible to insert the gauge member 75. I prefer to select a slot or groove width differing sufficiently from the thickness of gauge member 75, namely, the distance between faces 65 and 66 thereof, so as to allow insertion of the gauge portions 75 into the respective slots so long as excessive twisting of the pin has not occurred. It may be noted further that I prefer that the thickness of the gauge portions 75 which extend into the slots 42 and 43 are adapted to be inserted in slots which are wider by an equal amount. That is to say, that the long arm of L-shaped member 64 may have a thickness X; while the sum of the widths of the spaces between that member and the opposed side wall faces of the respective groove 42 are equal to a distance Y, the groove having a width $(X+Y)$; while the other blade, 65 namely, the long arm portion of L-shaped member 58 has a thickness Z; and the slot 43 has a width of $(Y+Z)$.

Having thus described the disclosed embodiment of the invention, it will be apparent to those having ordinary skill in the art to which this invention pertains, that various modifications and changes may be made in the illustrative embodiment, without departing from the spirit or the scope of the appended claims.

Therefore, what is claimed as new and desired to be secured by Letters Patent is:

1. A gauge for a threaded pin which comprises a base member, means for releasably attaching said base member to a free end of the pin, said base member having a slot having a portion adjacent the end of the pin, an angle-shaped feeler member having one arm receivable in the slot with one edge of said arm in engagement with the free end of the pin and with faces of said arm in closely engaging relation with walls of the slot and a second arm extending longitudinally of the pin, and means on the second arm for registering with the pin to indicate elongation of the pin.
2. A gauge for a threaded pin having a longitudinal slot in a side face thereof which comprises a base member, means for releasably attaching said base member to a free end of the pin, said base member having a slot having a portion adjacent the end of the pin, an angle-shaped feeler member having one arm receivable in the slot of the base member with one edge of said arm in engagement with the free end of the pin and with faces of said arm in closely engaging relation with walls of the slot of the base member and a second arm extending longitudinally of the pin and along the slot in the pin, and means on the second arm for registering with the pin to indicate elongation of the pin, the thickness of the second arm being slightly less than the width of the slot in the side face of the pin, whereby the spacing between faces of the second arm and walls of the slot in the pin indicates deformation of the pin.
3. A gauge for a threaded pin having an axial bore which comprises a base member, means for releasably attaching said base member to a free end of the pin at the axial bore, said base member having a radially extending slot having a portion adjacent the end of the pin, an angle-shaped feeler member having one arm receivable in the slot with one edge of said arm in engagement with the free end of the pin and with faces of said arm in closely engaging relation with walls of the slot and a second arm extending longitudinally of the pin, and means on the second arm for registering with the pin to indicate elongation of the pin.
4. In combination, a connector pin having a threaded body, a longitudinal slot in the threaded side of the pin, a gauge base having a slot therein, means for attaching the gauge base to the outer end of the pin with the slot of the gauge base adjacent the outer face and aligned with the slot in the pin, and an angle-shaped feeler member having an upper arm receivable in the slot of the gauge base with faces of said upper arm in closely engaging relation with walls of the slot of the gauge base and a lower arm extending into the slot of the body, the width of the lower arm being slightly less than the width of the body slot in which it is received, whereby distortion of the pin at the slot can be determined by the spacing of the lower arm from the sides of the slot in which it is received.
5. In combination, a connector pin having a threaded body and an inner shoulder at one end of the body substantially perpendicular to the axis of the body and extending outwardly therefrom, the body terminating in an outer face substantially perpendicular to the axis of the body, there being a longitudinal slot in the threaded side of the body, a gauge base having a slot therein, means for releasably attaching the gauge base to the outer face of the body with the slot of the gauge base adjacent the outer face and aligned with the slot in the body, and an angle-shaped feeler member having an upper arm receivable in the slot of the gauge base with faces of said upper arm in closely engaging relation with walls of the slot of the gauge base and one edge of the upper arm engaging the outer face of the body and a lower arm extending along the slot in the body, the thickness of the lower arm being slightly less than the width of the body slot, whereby distortion of the pin at the body slot can be determined by the spacing of the lower arm from the sides of the body slot, the lower

end of the lower arm terminating adjacent the shoulder, whereby elongation of the body can be detected.

6. In combination, a connector pin having a frustoconic, threaded body and an inner shoulder substantially perpendicular to the axis of the body and extending outwardly therefrom, the body terminating in an outer face substantially perpendicular to the axis of the body, there being a longitudinal slot in the threaded side of the pin, the inner wall of the slot being substantially parallel to the axis of the body, the slot terminating adjacent the inner shoulder, a gauge base having a slot therein, means for attaching the gauge base to the outer end of the pin with the slot of the gauge base adjacent the outer face and aligned with the slot in the pin, and an angle-shaped feeler member having an upper arm receivable in the slot of the gauge base, with faces of said upper arm in closely engaging relation with walls of the slot of the gauge base and one edge of the upper arm engaging the outer face, and a lower arm extending into the slot of the body, the width of the lower arm being slightly less than the width of the body slot in which it is received, whereby distortion of the pin at the slot can be determined by the spacing of the lower arm from the sides of the slot in which it is received, the lower end of the lower arm terminating adjacent the shoulder, whereby elongation of the body can be detected.

7. In combination, a connector pin having a frustoconic, threaded body and an inner shoulder substantially

perpendicular to the axis of the body and extending outwardly therefrom, the body terminating in an outer face substantially perpendicular to the axis of the body, there being a threaded axial bore and a pair of radial grooves in the outer face, there being longitudinal slots in the threaded sides of the pin in registry with the grooves, the inner walls of the slots being substantially parallel to the axis of the body, the slots terminating adjacent the inner shoulder, a gauge base having a pair of radially extending slots, screw means for attaching the gauge base to the outer end of the pin in the axial bore with the radial slots of the gauge base aligned with the grooves and slots in the pin, and a pair of angle-shaped feeler members, each of the feeler members having an upper arm receivable in one of the slots of the gauge base, with faces of the upper arm in closely engaging relation with walls of one of the slots of the gauge base and one edge of the upper arm being received in one of the radial grooves, and a lower arm extending into one of the slots of the body, the width of each lower arm being slightly less than the width of the body slot in which it is received, whereby distortion of the pin at the slot can be determined by the spacing of each lower arm from the sides of the slot in which it is received, the lower ends of the lower arms terminating adjacent the shoulder, whereby elongation of the body can be detected.
